UNITED STATES PATENT OFFICE.

ROBERT MILLER, OF NEW YORK, N. Y.

FOUR-CYCLE INTERNAL-COMBUSTION ENGINE.

979,082.

Specification of Letters Patent. Patented Dec. 20, 1910.

Application filed March 1, 1910. Serial No. 546,714.

To all whom it may concern:

Be it known that I, ROBERT MILLER, a citizen of the United States, residing at 614 Beach Terrace, in the city, county, and State of New York, have invented a new and useful Improvement in Four-Cycle Internal-Combustion Engines, of which the following is a specification.

My invention relates to four cycle internal combustion engines, and the objects of my invention are first to provide an engine which shall work efficiently at high engine speeds; second to provide a valve arrangement which will make a larger effective opening than those now in use; third to provide an engine which will scavenge its cylinder more thoroughly than those now in use.

I accomplish the result which I seek by the mechanism shown in the drawings.

Similar letters refer to similar parts throughout the drawings.

Figure 1 is a sectional elevation of my engine taken in a plane at right angles to the axis of the crank shaft; Fig. 2 is a sectional elevation of my engine taken in the plane of the axis of the crank shaft; Fig. 3 is a horizontal section of my device taken on the plane X X (Fig. 1), with the ports Q on the same level as the ports O; Fig. 4 is a horizontal section of my device taken on the plane Y Y (Fig. 2), with the ports R on the same level as the ports P; Fig. 5 is a horizontal section of my device taken on the plane N (Fig. 1), with the ports N''' on the same level as the port N'; Fig. 6 is a diagrammatic section in elevation of my device at the top of the compression stroke, at about the moment of firing; Fig. 7 is a diagrammatic section in elevation of my device at the bottom of the explosion stroke; Fig. 8 is a diagrammatic section in elevation of my device at the top of the exhaust stroke; Fig. 9 is a diagrammatic section in elevation of my device just before the bottom of the intake stroke.

For the sake of clearness and simplicity in Figs. 6, 7, 8 and 9, the ports are the only parts of said figures which are lettered.

A is the cylinder head; B is the cylinder; C is the water jacket space in the cylinder; D is a sliding sleeve traveling vertically inside of cylinder B; E is a flywheel; F is the main crank; G is the main connecting rod; H is the piston; J is the spark plug; K is the crank case; N' is an auxiliary exhaust

port in cylinder B, so located that its bottom is level with the top of piston H at lower dead center; N'' is the auxiliary exhaust connection; N''' are auxiliary exhaust ports 60 in sleeve D; O are the main exhaust ports in cylinder B; P are the intake ports in cylinder B, these ports have their bottom about level with the top of auxiliary exhaust ports N'; P' is the intake connection; Q are 65 the main exhaust ports in sleeve D; R are the intake ports in sleeve D; S is the main crank shaft; a is a gear wheel; b is a pinion half the diameter of wheel a and meshed into wheel a; pinion b is fixed with reference 70 to main shaft S; f is a crank connecting wheel a to connecting rod d; d is a gear connecting rod joining crank f to sleeve D.

The operation of my device is as follows: Fig. 6 shows the engine at the top of the 75 stroke, at full compression, and at the moment of firing. At this point, the ports are all closed. As soon as the charge explodes in cylinder B, piston H is thereby driven downward, and crank F is thereby rotated 80 in the direction shown by the arrow in Fig. 6. Thereupon by reason of the relation between pinion a and gear wheel b and connecting rod d, sleeve D begins to descend, with the result that at the bottom of the explosion 85 stroke, sleeve D has descended so far that auxiliary exhaust ports N''' and N' register with each other, and the auxiliary exhaust takes place, as shown in Fig. 7. It will also be noted by reference to Fig. 7, that while 90 the auxiliary exhaust ports N''' and N' are fully open, the main exhaust ports Q and O are just beginning to open. As the rotary motion of crank F continues, the piston H begins to rise until it reaches the top of the 95 exhaust stroke, as shown in Fig. 8, at which time exhaust ports Q and O are fully open. It will be noted, by reference to Fig. 8 that sleeve D is now traveling upward, so that 100 ports Q and O are closing. As the revolution of crank F continues on the downward intake stroke, the piston H descends and the sleeve D ascends, until they reach the relative positions shown in Fig. 9, at which time 105 exhaust ports O and Q are closed, auxiliary exhaust ports N' and N'' are closed, and intake ports R and P are open. As piston H has been descending with exhaust ports O and Q closed, a partial vacuum has been created inside of cylinder B, and as soon as 110 intake ports R and P open, the charge rushes into cylinder B. As the rotary motion of

crank F continues, the intake ports P R close, the main exhaust ports O and Q remain closed, and the charge is compressed up to the moment of firing, as shown in Fig. 6, thus completing the cycle of the engine's operation.

The construction allowing in a four cycle engine a charge admission very much delayed from what is usually done, is essentially new, and alters not only the structure but the results achieved as well. For example the residual gases remaining in the clearance have a longer time to cool before the admission of the new charge. This cooling results in their shrinkage and allows a larger live charge to be drawn in. Also the residual gases being thus cooled are less apt to ignite the entering charge if said charge be lean. Also, by delaying the admission of the charge until a considerable vacuum is built up in the cylinder, the charge enters with a rush so that inertia effects can be utilized to ram a full charge into the cylinder. In this respect, the construction allowing an inlet port encompassing the cylinder, said inertia effect has little to oppose it, so that a full charge is assured.

I claim:

1. In four cycle internal combustion engines, in combination, a piston; a main crank shaft; a connecting rod connecting said piston and said crank shaft; a cylinder having main exhaust ports in its upper portion, having auxiliary exhaust ports in its lower portion and having intake ports slightly above said auxiliary exhaust ports; a sleeve fitting closely within said cylinder and outside of said piston, and free to move to a limited extent up and down with relation to said cylinder, said sleeve having main exhaust ports in its upper portion (said ports registering in plan with said main exhaust ports in said cylinder), and having auxiliary exhaust ports in its lower portion (said ports registering in plan with said auxiliary exhaust ports in said cylinder), and having intake ports slightly above said auxiliary exhaust ports (said intake ports registering in plan with said intake ports in said cylinder); a gear wheel; a gear connecting rod connecting said gear wheel to said sleeve; a pinion of one half the diameter of said gear wheel, and meshed into said gear wheel, said pinion being fixed to and concentric with said main crank shaft; said crank shaft, pinion, gear wheel, gear connecting rod, sleeve, piston and connecting rod all coöperating whereby all of said ports are closed during the compression stroke and until almost the bottom of the explosion stroke, and whereby said auxiliary exhaust ports open at the bottom of the explosion stroke, and whereby said main exhaust ports remain open during the entire exhaust stroke, and whereby said main ex-

haust ports and said auxiliary ports remain closed during the intake stroke, and whereby said intake ports open near the bottom of said intake stroke.

2. In four cycle internal combustion engines, in combination, a piston; a main crank shaft; a connecting rod connecting said piston and said crank shaft; a cylinder having main exhaust ports in its upper portion, having auxiliary exhaust ports in its lower portion, and having intake ports slightly above said auxiliary exhaust ports; a sleeve fitting closely within said cylinder and outside of said piston, and free to move to a limited extent up and down with relation to said cylinder, said sleeve having main exhaust ports in its upper portion (said ports registering in plan with said main exhaust ports in said cylinder), and having auxiliary exhaust ports in its lower portion (said ports registering in plan with said auxiliary exhaust ports in said cylinder), and having intake ports slightly above said auxiliary exhaust ports (said intake ports registering in plan with said intake ports in said cylinder); means for moving said sleeve to a limited degree up and down in said cylinder; said crank shaft, sleeve, moving means, piston and connecting rod all coöperating whereby all of said ports are closed during the compression stroke and until almost the bottom of the explosion stroke, and whereby said auxiliary exhaust ports open at the bottom of the explosion stroke, and whereby said main exhaust ports remain open during the entire exhaust stroke, and whereby said main exhaust ports and said auxiliary exhaust ports remain closed during the intake stroke, and whereby said intake ports open near the bottom of said intake stroke.

3. In four cycle internal combustion engines, in combination, a piston; a main crank shaft; a connecting rod connecting said piston and said crank shaft; a cylinder having exhaust ports in its upper portion, and having intake ports in its lower portion; a sleeve fitting closely within said cylinder and outside of said piston, and free to move to a limited extent up and down with relation to said cylinder, said sleeve having exhaust ports in its upper portion (said ports registering in plan with said exhaust ports in said cylinder), and having intake ports in its lower portion (said intake ports registering in plan with said intake ports in said cylinder); a gear wheel; a gear connecting rod connecting said gear wheel to said sleeve; a pinion of one half the diameter of said gear wheel, and meshed into said gear wheel, said pinion being fixed to and concentric with said main crank shaft; said crank shaft, pinion, gear wheel, gear connecting rod, sleeve, piston and connecting rod all coöperating whereby all of said ports are closed during the compression stroke and until almost the bottom of the explosion stroke, and whereby said auxiliary exhaust ports open at the bottom of the explosion stroke, and whereby said main exhaust ports remain open during the entire exhaust stroke, and whereby said main ex-

until almost the bottom of the explosion stroke, and whereby said exhaust ports remain closed during the intake stroke, and whereby said intake ports open near the bottom of said intake stroke.

4. In four cycle internal combustion engines, in combination, a piston; a main crank shaft; a connecting rod connecting said piston and said crank shaft; a cylinder having exhaust ports in its upper portion, and having intake ports in its lower portion; a sleeve fitting closely within said cylinder and outside of said piston, and free to move to a limited extent up and down with relation to said cylinder, said sleeve having exhaust ports in its upper portion (said ports registering in plan with said exhaust ports in said cylinder), and having intake ports in

its lower portion (said intake ports registering in plan with said intake ports in said cylinder); means for moving said sleeve to a limited degree up and down in said cylinder; said crank shaft, sleeve, moving means, piston and connecting rod all coöperating whereby all of said ports are closed during the compression stroke and until almost the bottom of the explosion stroke, and whereby said exhaust ports remain open during the entire exhaust stroke, and whereby said exhaust ports remain closed during the intake stroke, and whereby said intake ports open near the bottom of said intake stroke.

ROBERT MILLER.
